COMPRESSOR

James A. Sinclair, Houston, Tex.

Application November 11, 1944, Serial No. 562,928

7 Claims. (Cl. 230—108)

1

The present invention relates to compressors and particularly to compressors for compressing a gas or vapor medium by means of the application of pressure to a liquid medium in which the gaseous medium is entrained. It is based primarily upon the principle that if a liquid having bubbles of gas entrained in it is subjected to pressure, the gas bubbles will be compressed accordingly, whereby the separation of the gas from the liquid at the higher pressure will result in the production of compressed gas.

The primary object of the present invention is the provision of a new and improved compressor.

Another object of the present invention is to provide a new and improved centrifugal compressor wherein a mixture of gaseous and liquid media is subjected to pressure and then discharged, and wherein the compressed gaseous medium is separated from the liquid medium at the higher pressure.

Another object of the present invention is to provide a new and improved compressor wherein pressure is simultaneously applied to a mixture of liquid and gaseous media and wherein the two are continuously separated at high pressure.

Another object of the present invention is to provide a new and improved compressor utilizing a continuous flow of a liquid medium to entrain a gaseous medium to be compressed and including means for applying pressure to the mixture and then separating the compressed gas from the liquid at the high pressure.

A still further object of the present invention is the provision of a new and improved compressor including means for creating a cyclic flow of liquid, in a portion of which cycle the liquid is subjected to high pressure, means for supplying gas to be compressed for mixture with said liquid at a point in the cycle ahead of the high pressure point, and means for separating the compressed gas at a point in the cycle behind the high pressure point.

Another object of the present invention is to provide a new and improved centrifugal compressor utilizing liquid for compressing gas and wherein the discharged liquid is utilized as a source of power for actuating the centrifugal means.

Another object of the present invention resides in a new and improved mechanical construction for a centrifugal liquid type gas compressor.

Other objects and advantages of the present invention will become apparent from the ensuing description, in the course of which reference is had to the accompanying drawing, the single

2

figure of which represents a presently preferred embodiment of the invention.

The compressor of the present invention, as already indicated, is based upon the principle that if a liquid having gas entrained in it is subjected to pressure, the gas will be compressed accordingly, so that if the two fluids are separated at the higher pressure, a compressed gas will result. In the apparatus illustrated in the figure, 10 gas is drawn into a stream of liquid at low pressure, the mixture is subjected to high pressure, the gas and liquid are separated at the resulting high pressure, the compressed gas is drawn off, and the liquid is returned to provide an advantageous cyclic operation.

Turning now to the figure, it may be noted that the compressor is indicated as a whole by the reference character 10. It includes a support or frame 12 including a plurality of spaced apart legs 14 supporting an upper central yoke 16. The compressor is adapted to be secured in suitable manner upon a base or foundation 18, above which is located a quantity of liquid 20 utilized for the purpose of compressing the gas.

25 Gas is supplied for mixture with the liquid at low pressure through suitable means, such as tubes, nozzles, or as illustrated, through a conduit 22 having a perforated plate 24 at its upper end disposed a short distance below the surface of the liquid. The liquid may be water and the gas may be air although other liquids and gases (including vapors) may be used. If atmospheric air is used as the gas, then the inlet end of conduit 22 should be open to atmosphere and above or beyond the liquid 20.

The compressor includes a rotor indicated generally by the reference character 30 suspended centrally from the frame and adapted to be drawn by suitable means (not shown) through 40 a vertically disposed drive shaft 32 and as by a pulley 34 or the like secured to the upper end of the shaft. It is preferred but not necessary that the pressure supplying means be secured to the lower end of the shaft 32. In the instant 45 case the pressure supplying means includes an impeller or the like 36 secured to the lower end of the shaft. The impeller has a generally downwardly facing inlet 38 coaxially disposed relative to the shaft and to the conduit. It is preferred that the lower end of the inlet be disposed a short distance above the upper end of conduit 22 and that it be of approximately the same size. If desired, the conduit 22 may be mounted for vertical adjustment to enable variation of the distance between it and inlet 38.

In operation the impeller creates a region of negative pressure at the inlet with the result that gas from conduit 22 is entrained with the liquid and the mixture is caused to flow upwardly within the rotor 30. The impeller includes a radially and upwardly extending passageway 40 of gradually decreasing cross section area, and it is preferred that, instead of a single annular passageway, the passageway be divided into a plurality of passageways by the vanes 42. The rotor terminates in an upper, generally cup-shaped portion 44 having a diameter greater than the inlet portion. The vanes 42 are continued up the inner sides of the outer portion to the top.

The impeller subjects the mixture of liquid and gas to high pressure and the mixture is discharged into a separation chamber 50 disposed above the impeller and constituted in part by the impeller and a casing 52 surrounding the impeller and rotatable with it.

The gas and liquid are separated in the separation chamber at high pressure and the gas is discharged to a suitable reservoir through a gas discharge conduit 54, the downwardly extending portion 56 of which extends within the casing and below the top of the impeller. It has a series of openings 58 providing communication with the upper portion of the separation chamber so that the compressed air may flow into the conduit 54—56 through the openings 58 and thence into the discharge chamber.

The casing 52 is preferably constructed into two parts 52L and 52U, the former of which is secured as by a plurality of screw bolts 60 to the impeller and the latter of which is secured to the former by a plurality of bolts 62.

The liquid separated from the gas in the separation chamber is returned to the liquid source 20 through a generally downwardly and inwardly extending passageway 64 constituted by the outer portion of the impeller and the casing 52. It is preferred that the liquid, which is under pressure, be utilized to impart rotation to the impeller and this is accomplished by providing a series of jets, nozzles or reaction blades 66 at the lower inner end of passageway 64 through which the liquid is returned to the source.

Leakage of air from within the separation chamber is prevented by a rotary seal 68 including a sealing ring 70 secured to the portion 56 of the discharge conduit and cooperating with a downwardly extending portion 72 of the upper casing member 52U. Leakage is additionally prevented by oil 74 within a groove 76 constituted by portions of the sealing ring 70 and casing flange 72.

Leakage of compressed air upwardly along the shaft from the discharge conduit 54 is prevented by a rotary seal 78 which may be of any suitable construction.

The vertical shaft 32 is journaled in spaced apart ball bearings 80 and 82, the former of which is supported at the upper end of the gas discharge conduit 52 and the second at the lower end of the conduit. The lower end of the conduit is provided with a series of webs 84 supporting the inner race of the ball bearing and spaced apart to provide additional communication between conduit 54 and the separation chamber.

In operation, the impeller is rotated by rotation of the drive shaft 32, which, it may be remembered, may be rotated by any suitable means. The rotation of the impeller 36 creates a region of negative pressure at the inlet 38 with the result that gas from conduit 22 and liquid from

source 20 are drawn upwardly into the impeller. The centrifugal force subjects the mixture to a high pressure and the resulting mixture is discharged through passageways 40 into the separation chamber 50. Separation of the gas from the liquid does not occur in passageways 40 because the latter are substantially radial and the fluid velocity is great enough to overcome any tendency of the gas to separate. However, when the mixture reaches the separation chamber, where the flow is more nearly axial, the gas flows to the fluid surfaces and to the fluid-free portion of the chamber. From the chamber the high pressure gas flows through apertures 58 (and spaces between webs 84) into the gas discharge conduit 54 from whence it may be led to a suitable gas reservoir. The liquid returns to the source 20 through the passageway 64 and the reaction devices 66.

From the foregoing description, it may be noted that the compressor of the present invention is characterized by its simplicity, its continuous cyclic utilization of liquid to compress the gas, and also by its utilization of the liquid itself to impart rotation to the impeller.

While but a single embodiment of the invention has been illustrated and described, it should be understood that the specific details of the embodiment are not to be limitative, except in so far as set forth in the appended claims.

Having thus described my invention, what I claim as new and desire to secure by Letters Patent of the United States, is:

1. A compressor for compressing a gaseous medium by applying pressure thereto through a liquid medium, including in combination, centrifugal means rotatable about a vertical axis for drawing a mixture of the two media from separate sources thereof and for bringing them to a high pressure, means including a centrally open chamber rotating with and into which the rotatable centrifugal means discharges for separating the media at high pressure, means for drawing off the compressed gaseous medium by a generally upward flow, and means for returning the liquid medium to its source by a generally downward flow.

2. A compressor for compressing a gaseous medium by applying pressure thereto through a liquid medium, including in combination, centrifugal means for drawing a mixture of the two media and bringing them to a high pressure, means for separating the media at high pressure, said means including a centrally open separation chamber rotatable with said centrifugal means into which the media are discharged, means including a stationary conduit extending centrally into said separation chamber for drawing off the compressed gaseous medium from said separation chamber by an upward flow generally axially of said centrifugal means, and means for drawing off the liquid medium by a generally downward flow near the outer periphery of said centrifugal means.

3. A compressor, including in combination, an impeller mounted for rotation about a substantially vertical axis and having a substantially coaxial inlet at its lower end and a generally annular outlet at its upper peripheral end, a centrally open separation chamber located above and communicating with said outlet, a first discharge outlet located substantially coaxially of and above the impeller and communicating with said chamber, and a second generally annular discharge passage located near the lower end of said

impeller and communicating with the separation chamber near the periphery of the impeller.

4. A compressor, including in combination, an impeller mounted for rotation about a substantially vertical axis and having an inlet at its lower end, an outlet at its upper end spaced radially outward from said inlet and a rim forming part of the impeller and extending generally upwardly from said outlet, a centrally open separation chamber located above and communicating with said outlet and including a casing defining portion above and radially beyond said outlet and rim, and a pair of discharge outlets communicating with the separation chamber.

5. A compressor, including in combination, an impeller mounted for rotation about a substantially vertical axis and having a substantially coaxial inlet at its lower end and a generally annular outlet at its upper peripheral end, a separation chamber located above and communicating with said outlet, said chamber being defined in part by a casing forming part of the impeller, a first discharge outlet located substantially coaxially of and above the impeller and communicating with said chamber, and a second discharge outlet located near the lower end of said impeller and communicating with the separation chamber between the impeller and said casing.

6. A compressor, including in combination, a shaft rotatable about a substantially vertical axis, an impeller mounted upon said shaft, said impeller including a lower portion defining a coaxial inlet and an upper enlarged generally cup-shaped portion terminating in a generally upwardly and outwardly extending peripheral outlet, a casing into which said outlet discharges secured to the impeller and extending radially outward beyond and axially below and above the enlarged portion of the impeller, the portion extending above defining a separation chamber and

5

the portion extending below defining a generally annular outlet passageway, a first discharge outlet extending downwardly into said separation chamber and having openings providing communication with the chamber, and a second discharge outlet constituted by openings at the lower inner end of the casing.

7. A compressor, including in combination, a drive shaft rotatable about a substantially vertical axis, an impeller mounted upon said shaft, said impeller including a lower portion defining a coaxial inlet and an upper enlarged generally cup-shaped portion terminating in a generally upwardly and outwardly extending peripheral outlet, a casing into which said outlet discharges secured to the impeller and extending radially outward beyond and axially below and above the enlarged portion of the impeller, the portion extending above defining a separation chamber and the portion extending below defining a generally annular outlet passageway, a first discharge outlet extending downwardly into said separation chamber and surrounding the shaft, said passageway having openings providing communication with the chamber, and a second discharge outlet constituted by openings at the lower inner end of the casing, said outlet including reaction means for imparting rotation to the impeller.
